DISPENSER FOR TAPE

Leif Blodee, 291 W. 12th St., Holland, Mich.
Filed Dec. 5, 1961, Ser. No. 157,097
2 Claims. (Cl. 225—65)

This invention relates to tape dispensers, and more particularly to a cutting device adapted to be attached to a hollow roll of tape.

There are presently on the market a large variety of tape dispensers into which a roll of tape can be inserted, and from which neatly cut tape pieces of any desired length can be readily obtained. In many instances, however, it is either impractical or uneconomical to use a tape dispenser into which a roll of tape can be inserted, particularly if the roll involved is of considerable size and consequently requires a rather bulky and heavy dispenser. It has therefore become desirable to provide a simple tape cutter which can be attached directly to a roll of tape. Inasmuch as such devices, however, are most useful under circumstances in which the weight, awkwardness, and expense of a regular tape dispenser was a problem, it was necessary to provide a floating cutter (i.e. a cutter readily movable along the perimeter of the tape roll) which was a very simple construction and light weight so as to allow easy, safe handling and adjustment and be expendable. This in turn required that the cutting mechanism be constructed of a very few simple, inexpensive parts which did not require any machining or other complicated manufacturing processes. In order to obtain accurate action of the cutter, it was also necessary to provide the cutter with means permitting its continuous and easy adjustment to keep it taut against the surface of the tape as the tape was used up.

The present invention solves these problems by providing a simple mechanism consisting of a backing member adapted to ride along the inner perimeter of the tape roll, a cutting member riding on the outer perimeter of the tape roll, and a generally U-shaped flexible metal strip connecting the cutting member to the backing member. The backing member is hollowed out to form a receptacle having a pair of cylindrical chambers into which the ends of the U-shaped metal strip can be pushed. As the tape on the roll is used up, the metal strips are pushed farther and farther into the backing member, where they are bent and rolled up by the walls of the cylindrical chambers. A pair of resilient and sharply pointed wedging fingers are provided inside the backing member to prevent the strips from being withdrawn.

It is therefore the object of the invention to provide a simple, expendable, and safe tape cutter which can be simply mounted on a hollow roll of tape and can be progressively adjusted to compensate for the variation in thickness of the roll of tape as the tape is used up.

It is another object of the invention to provide a device as described above which can be simply progressively adjusted merely by squeezing the cutter and backing member against the tape roll.

It is a further object of the invention to provide a device as described above in which the cutter and backing member are connected by flexible metal strips whose ends are automatically rolled up within the backing member as the device is adjusted.

It is still another object of the invention to provide a device as described above which cannot be loosened once it has been tightened.

These and other objects of this invention will be apparent from the following specification taken in connection with the attached drawings in which:

FIG. 1 is a perspective view showing the device of this invention attached to a roll of tape; and

2

FIG. 2 is a partial end view, partially in section, of the device of FIG. 1.

Basically, the device of the invention is clamped onto a roll of tape by a U-shaped metal strip extending between the cutter on the outside of the tape roll and a backing member or receptacle on the inside of the tape roll. The receptacle has a pair of cylindrical chambers in which the ends of the metal strip are automatically coiled and stored as the ends are progressively inserted into the chambers when the cutter and backing member are periodically squeezed together as the thickness of the tape on the roll diminishes.

As will be best seen in FIG. 2, the device 10 consists of a backing member or receptacle 12 containing a pair of cylindrical chambers 14. A cutter 16 is held against the tape 22 by the central portion 24 of a unidirectionally flexible metal strip 26. Side pieces 18, 20 are provided to secure the strip 26 to the cutter 16. The ends 28 of the metal strip 26 are tangentially inserted in the chambers 14 through slots 30. Due to the cylindrical shape of chambers 14, the ends 28 tend to coil up in chambers 14 as they are pushed further into slot 30. A spring 32 is embedded in the backing member 12 in such a manner as not to interfere with the coiling of ends 28 or their insertion into the chambers 14, but to form a wedge preventing withdrawal of the strip ends 28 from the chambers 14.

In operation, the backing member 12 is applied to the inside of the tape roll. The cutter 16 with the ends 28 of strip 26 extending therefrom is then placed on the outside of the tape roll, and the ends 28 are inserted into the slot 30. The backing member 12 and cutter 16 are then simply squeezed together as far as the tape 22 will permit them to go. As they are squeezed together, the ends 28 penetrate into the chambers 14 and are coiled up therein. The entire device may now be floatingly moved along the tape roll as the tape is debited therefrom. As the thickness of the tape 22 diminishes as the tape is used up, the slack of the strip 26 can be taken up simply by again squeezing the backing member and the cutter together until they again become seated firmly against the inner and outer perimeters of the tape roll 22. The wedge action of spring 32 effectively prevents separation of the cutter and backing member and thereby precludes the device from becoming misadjusted or coming apart.

It will be seen that I have provided a simple but effective cutter mechanism for hollow tape rolls in which the ends of the adjusting strip 26 are safely stored away in the backing member to prevent injury to the operator, or interference with the handling of the tape roll, in the use of the device. Obviously, many modifications of this invention are possible within the spirit of the invention itself, and the invention is therefore not to be deemed limited by the embodiment shown, but only by the scope of the following claims.

I claim:

1. An expendable floating tape cutting device for use on a hollow roll of tape, comprising: a strip receptacle dimensioned to be positioned against the inner perimeter of said roll; a cutter adapted to be positioned against the outer perimeter of said roll; and a strip of unidirectionally flexible material adapted to hold said cutter against said tape, said strip having an end portion adapted to be inserted into said receptacle; said receptacle having a cylindrical chamber for receiving said strip end and guiding it into roll form as it is inserted therein, and resilient means allowing said strip end to be pushed into said chamber to keep said cutter tight against said tape roll as said tape is used up but preventing its withdrawal therefrom.
2. An expendable floating tape cutting device for use on a hollow roll of tape, comprising: a strip receptacle

dimensioned to be positioned against the inner perimeter of said roll; a cutter adapted to be positioned against the outer perimeter of said roll; and a strip of unidirectionally flexible material having a central portion adapted to be placed around said cutter to hold it against said tape, and a pair of end portions adapted to be inserted into said receptacle; said receptacle having a pair of slots for insertion of said strip ends, a pair of cylindrical chambers for receiving said strip ends and guiding them into roll form as they are inserted therein, and resilient fingers allowing 10

4
said strip ends to be pushed into said chambers to keep said cutter tight against said tape roll as said tape is used up but preventing their withdrawal therefrom.
